Inventor:

EDWIN H. BRODEN,

D. Anthony Usina
his Attorney.

UNITED STATES PATENT OFFICE.

EDWIN H. BRODEN, OF EDGEWOOD BOROUGH, PENNSYLVANIA, ASSIGNOR TO THE AMERICAN STEEL AND WIRE COMPANY OF NEW JERSEY, A CORPORATION OF NEW JERSEY.

PLIERS.

Application filed March 19, 1924. Serial No. 700,317.

To all whom it may concern:

Be it known that I, EDWIN H. BRODEN, a citizen of the United States, and resident of Edgewood Borough, in the county of Allegheny and State of Pennsylvania, have invented certain new and useful Improvements in Pliers, of which the following is a specification.

This invention relates to wire cutting pliers, and has for its particular object the provision of such pliers having safety means for holding the wire that has been cut.

Another object is to adapt such safety means to the well known and accepted form of "button pliers" now in use, without materially changing their form or adding to their weight.

A further object is to provide pliers having the novel design, construction, and combination of parts hereinafter described and illustrated in the accompanying drawings.

Heretofore pliers of this class have been provided with cutting notches, and have come into general use. However, oftentimes the wire when cut will fly and strike either the operator or one of his fellow workmen, and many times has caused serious injury to their eyes and other parts of their bodies. Especially is this true in cutting barbed wire.

Within the last few years those skilled in this art, spurred on by the numerous safety first campaigns, have attempted to provide pliers of this class with means for holding cut wire. However, the pliers heretofore provided with means for holding the cut wire have been thoroughly tested and discarded as unsuccessful.

The present pliers are composed of few parts, are of substantially the same weight and size of the standard pliers now in use, and are not weakened in any manner by the addition of the safety means.

In the drawings—

Figure 1 is a plan of a tool embodying my invention;

Fig. 2 is a side elevation thereof;

Fig. 3 is a plan of the tool in open position, the handle portions being broken away;

Fig. 4 is a side elevation of the tool in open position;

Fig. 5 is a plan of the tool, showing a wire gripped therein;

Fig. 6 is a side elevation of the tool, showing a wire gripped therein;

Fig. 7 is a plan, showing details of the wire clamping plate forming part of my improved tool;

Fig. 8 is a plan showing the construction of the spring forming part of the wire clamping mechanism; and

Fig. 9 is a plan, similar to Fig. 5, showing a modified form of wire-gripping mechanism.

Referring more particularly to the drawings, the letters A and B designate the two limbs of my improved pliers, which are constructed to form gripping jaws 3, handle portions 4, and disk-bearing joint portions 5. The disk-bearing joint portions 5 are formed in the usual manner by forming an enlarged circular bearing disk portion between the jaw or head 3 and the handle 4 of each limb, and cutting said disk portions away to form the usual interlocking joint, pivotally held together by a pivot pin 6.

The portions 5 also form what may be termed "cutting jaws" and are cut away to form notches or recesses 7, 8 and 9, the inner edges of which act as cutting blades to cut wire or the like, the notches in the portions 5 being arranged in pairs and co-operating to form continuous grooves or recesses for the reception of the wire to be cut.

A wire clamping plate 10 is positioned on the outside face of each of the bearing portions or cutting jaws 5. The plates 10 are pivotally mounted in position on a pivot pin 6a which passes centrally through the main pivot 6, and therefore are movable about a common axis with limbs A and B. Each of the plates 10 is provided on its inner side face with a recess 12 in which is mounted a spring 14 adapted to engage a pin 11 secured in the respective limbs, thus providing a yieldable connection between the plates 10 and limbs A and B, whereby the plates will yield to permit engagement with varying sizes of wire.

The plates 10 are provided with notches 15, 16 and 17 corresponding with the notches 7, 8 and 9 in the disks 5, and the notches 15, 16 and 17 are adapted to align with the notches 7, 8 and 9 when the tool is in wire receiving position to form a continuous wire receiving recess or slot.

The side walls of the notches 7, 8 and 9 are square, as are also the side walls of the notches 15, 16 and 17, so as to form wire gripping faces for clamping the wire.

5 In operation, when the pliers are moved to open position the limbs A and B and plates 10 will all move about their common axis so as to assume a position in which the notches 7, 8 and 9 of the opposite disk or 10 cutting jaw portions 5 will move into alignment, and the notches 15, 16 and 17 of the plates 10 will also align, respectively, with the notches 7, 8 and 9 so as to form continuous wire receiving recesses or slots.

15 When the limbs A and B are moved to closed or cutting position the disk or cutting jaw portions 5 will rotate in opposite directions so as to bring the cutting edges of the recesses or notches 7, 8 and 9 into cutting engagement with the wire, and the plates 10 will move in a direction opposite the disks 5 which they abut, due to their being operatively connected by the springs 14 to the limb integral with and extending from the 20 opposite disk, so as to cause the side walls of the notches 15, 16 and 17 to engage and force the body of the cut wire against the side walls or faces of the recesses or notches 7, 8 and 9, thereby clamping the main body 25 of wire and the severed end in the recesses 7, 8 and 9 and preventing movement of the wire from cutting position.

The spring 14 which co-operates with the 30 pin 11 to form a yieldable operative connection for the plates 10 with the limbs A and B is adapted to yield so as to permit the plates 10 to operate against any size of wire within the limits of the cutting jaws.

40 In Fig. 9 I have shown a modified form of clamping plate 10 in which the recess or depression 12 is omitted and an opening 12^a is provided for fitting over the pin 11 and for receiving the flexing end of a leaf-spring 14^a formed integral with the plate or welded thereto as desired.

45 It will be understood that while I have described and illustrated my invention as applicable to wire cutting pliers, it may readily be applied to a cutting tool in which the gripping jaws 3 have been omitted,—that is, to a tool composed of a pair of limbs which terminate with the notched disks or cutting jaws 5. Other modifications in design and construction may also be made without departing from the scope of the appended claims.

I claim—

50 1. In a cutting tool, a pair of cutting and gripping members relatively movable about a common axis, and an independent gripping member co-operating with at least one of said cutting and gripping members and rotatable about said common axis.

60 2. In a cutting tool, a pair of cutting and gripping members relatively movable about

a common axis, and independent gripping members co-operating with each of said cutting and gripping members and rotatable about said common axis.

3. Pliers comprising a pair of limbs relatively movable about a common axis, said limbs each comprising a jaw portion, a handle portion, and a disk joint portion, said disk joint portions being arranged side by side and pivotally joined by a suitable pivot 70 pin, said disk portion of each limb being provided with wire cutting notches, the notches of each disk being adapted to align with the notches of the other disk when the pliers are in open position, and a gripping 75 member co-operating with at least one of said disk portions and movable about said common axis to grip the article being cut.

4. Pliers comprising a pair of limbs relatively movable about a common axis, said limbs each comprising a jaw portion, a handle portion, and a disk joint portion, said disk joint portions being arranged side by side and pivotally joined by a suitable pivot 80 pin, said disk portion of each limb being provided with wire cutting notches, the notches of each disk being adapted to align with the notches of the other disk when the pliers are in open position, and independent 85 gripping members co-operating with each of said disk portions and movable about said common axis to grip the article being cut.

5. In a hand implement for cutting wire and the like, a pair of jaws having a common pivotal mounting, each of said jaws having a recess formed therein to receive the wire to be cut, said recesses having co-operating cutting edges adapted to move into co-operative cutting relationship upon 100 operation of said jaws in one direction, and having the walls thereof shaped to form gripping faces, and a pair of gripping members carried by said pivotal mounting and having recesses adapted to be brought into 105 alignment with the recesses in said jaws to also receive the wire to be cut, said members each having an operative connection with one of said jaws so as to be simultaneously operable therewith upon cutting movement 110 of the jaws to cause the walls of the recesses therein to move toward the gripping faces of said first-mentioned recesses and automatically clamp the body of the wire adjacent the point of cutting to prevent movement 115 thereof from cutting position.

6. In a hand implement for cutting wire and the like, a pair of jaws having a common pivotal mounting, each of said jaws having a recess formed therein to receive the wire to be cut, said recesses having co-operating cutting edges adapted to move into 120 co-operative cutting relationship upon operation of said jaws in one direction, and having the walls thereof shaped to form grip- 125

ping faces, and a pair of gripping members carried by said pivotal mounting and having recesses adapted to be brought into alinement with the recesses in said jaws to 5 also receive the wire to be cut, said members each having a yielding operative connection with one of said jaws so as to be simultaneously operable therewith upon cutting movement of the jaws to cause the walls of 10 the recesses therein to move toward the gripping faces of said first-mentioned recesses and automatically clamp the body of the wire adjacent the point of cutting to prevent movement thereof from cutting position.

7. A combined pliers and wire cutting tool comprising a pair of limbs having a common pivotal mounting, each of said limbs comprising a gripping jaw portion, a handle portion, and a disk joint portion formed between said gripping jaw portion and said handle portion, said disk portions also serving as cutting jaws and being provided with a recess to receive the wire to be 20 cut, said recesses having co-operating cutting edges adapted to move into co-operative cutting relationship upon operation of said limbs in one direction, and having the walls thereof shaped to form gripping faces, and a pair of gripping members carried by said pivotal mounting and having recesses adapted to be brought into alinement with the recesses in said disk joint portions to 25 also receive the wire to be cut, said members each having an operative connection with one of the limbs of said tool so as to be simultaneously operable therewith upon cutting movement of said limb to cause the

walls of the recesses therein to move toward the gripping faces of said first-mentioned recesses and automatically clamp the body of the wire adjacent the point of cutting to prevent movement thereof from cutting position.

8. A combined pliers and wire cutting tool comprising a pair of limbs having a common pivotal mounting, each of said limbs comprising a gripping jaw portion, a handle portion, and a disk joint portion formed between said gripping jaw portion and said handle portion, said disk portions also serving as cutting jaws and being provided with a recess to receive the wire to be cut, said recesses having co-operating cutting edges adapted to move into co-operative cutting relationship upon operation of said limbs in one direction, and having the walls thereof shaped to form gripping faces, and a pair of gripping members carried by said pivotal mounting and having recesses adapted to be brought into alinement with the recesses in said disk joint portions to also receive the wire to be cut, said members each having a yielding operative connection with one of the limbs of said tool so as to be simultaneously operable therewith upon cutting movement of said limbs to cause the walls of the recesses therein to move toward the gripping faces of said first mentioned recesses and automatically clamp the body of the wire adjacent the point of cutting to prevent movement thereof from cutting position.

In testimony whereof, I have hereunto signed my name.

EDWIN H. BRODEN.
